US00D479992S

(12) **United States Design Patent** (10) **Patent No.:** **US D479,992 S**
Gehring et al. (45) **Date of Patent:** **** Sep. 30, 2003**

(54) **SNACK FOOD CONTAINER**

(75) Inventors: **Jay Edward Gehring**, Frisco, TX
 (US); **Joseph Paul Sagel**, Highland
 Village, TX (US)

(73) Assignee: **RECOT, Inc.**, Pleasanton, CA (US)

(**) Term: **14 Years**

(21) Appl. No.: **29/155,414**

(22) Filed: **Feb. 8, 2002**

(51) **LOC (7) Cl. 09-03**

(52) **U.S. Cl. D9/430**

OTHER PUBLICATIONS

Advertisement by Land O' Lakes showing a personal size container for beverages, trademarked as the "Grip." It also has a resealable top.

Primary Examiner—Prabhakar Deshmukh

(74) Attorney, Agent, or Firm—Colin P. Cahoon; Carstens, Yee & Cahoon, L.L.P.

(57) **CLAIM**

The ornamental design for a snack food container, as shown and described.

DESCRIPTION

FIG. 1 is a perspective view of the snack food container of the present invention;

FIG. 2 is a front elevation view of the snack food container of the present invention, with the rear elevation view a mirror image of the front elevation view;

FIG. 3 is a right elevation view of the snack food container of the present invention, with the left elevation view a mirror image of the right elevation view;

FIG. 4 is a top plan view of the snack food container of the present invention; and,

FIG. 5 is a bottom plan view of the snack food container of the present invention.

The broken lines defining a center portion of the snack food container, as shown in FIGS. 1, 2, and 3, are for illustrative purposes only and form no part of the claimed design.

1 Claim, 3 Drawing Sheets
